Cutler-Hammer, Inc., Milwaukee, Wis., a cor-
poration of Delaware

Application November 21, 1942, Serial No. 108,831

Term of patent 14 years

To all whom it may concern:

Be it known that I, Clyde F. Robbins, a citizen of the United States and a resident of Milwaukee, in the county of Milwaukee and State of Wisconsin, have invented a new, original, and ornamental Design for a One-Piece Molded Insulation Switch Base, of which the following is a specification, reference being had to the accompanying drawing, forming part thereof.

Figure 1 is a front elevational view of a one-

piece molded insulation switch base, showing my new design.

Fig. 2 is a side elevational view thereof.

Fig. 3 is a top plan view of said base.

Fig. 4 is a bottom plan view thereof.

I claim:

The ornamental design for a one-piece molded insulation switch base, as shown.

CLYDE F. ROBBINS.
